UNITED STATES PATENT OFFICE

EDWARD C. HANSON AND SYLVAN R. POPP, OF MINNEAPOLIS, MINNESOTA, ASSIGNEES
TO O. B. MCCLINTOCK COMPANY, OF MINNEAPOLIS, MINNESOTA, A CORPORATION OF
MINNESOTA

DEAL TRAY

Application filed May 16, 1931. Serial No. 537,770.

Our invention relates to deal trays intended for general use in closing a passage through a wall, partition or other closure so that there is not a direct opening therethrough and through which passage articles may be passed from one side of the closure to the other by manipulating the deal tray.

The invention is especially designed for use as a fixture in connection with a bullet-resisting enclosure for a cashier, teller or other person handling money and valuables to protect him as well as the valuables in his possession from a daylight hold-up by a bandit. The deal tray in itself is bullet-resisting and is mounted to close a passage through the lobby or customer's side of a bullet-resisting structure for the enclosure, or a passage in a wicket in said structure.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary elevation of the customer's side of a counter and a bullet-resisting partition in which the invention forms a part thereof;

Fig. 2 is a view partly in plan and partly in horizontal section taken substantially on the line 2—2 of Fig. 1, with some parts shown in different positions by means of broken lines;

Fig. 3 is a view partly in side elevation and partly in vertical section taken on the irregular line 3—3 of Fig. 2, on an enlarged scale;

Fig. 4 is a fragmentary detail view with some parts sectioned on the line 4—4 of Fig. 3, on an enlarged scale; and

Fig. 5 is a fragmentary detail view principally in section taken on the line 5—5 of Fig. 4.

The numeral 6 indicates a counter that is a closed structure that extends to the floor and the numeral 7 indicates a partition structure above said counter that separates what may be assumed to be a teller's cage 8 from a bank

lobby 9. Forming a part of the structure 7 is a wicket 10 hinged at 11 for opening movements over the counter 6 on the cage side thereof and provided with a lock 12. In the partition structure 7, on each side of the wicket 10, is a glass insert 13 and below each insert is a normally closed gun port 14. The wicket 10 has a glass insert 15 and on each side thereof is a voice panel 16.

The body of the counter 6, if of wood, will be lined or otherwise protected by a bullet-resisting material or substance and the partition structure 7 and wicket 10, as well as the glass inserts 13 and 15, are bullet-resisting.

By reference to Fig. 2 it will be noted that the partition structure 7 is so positioned above the counter 6 that a portion of said counter extends both on the lobby and cage side of said partition so that both the customer and teller may use the same. The top of the counter 6 directly under the wicket 10, and on which money or other valuables are placed in passing the same from the lobby side of the partition structure to the cage side thereof, is an insert 17 of glass or other suitable material.

This application has been assigned to the O. B. McClintock Company a Minnesota corporation and the parts thus far described in detail are the subject matter of a copending application filed by the inventors Oliver B. McClintock and Ferdinand A. Gabbert under date of May 18, 1931 and Serial Number 538,080 which has also been assigned to the above corporation.

Referring now in detail to the deal tray assembly which is the subject matter of the present application, the same is mounted in the frame of the wicket 10 below the glass insert 15 and bodily movable with said wicket during its opening and closing movements. The deal tray assembly, which is bullet-resisting, includes inner and outer concentric upright cylindrical casings 18 and 19, respectively, having closed tops and open bottoms that are closed by the counter 10 and its insert 17. Said outer casing 18 is rigidly secured to the frame of the wicket 10 below the glass insert 15 and the inner casing 19 is held

suspended within the fixed casing 18 for rotation about its vertical axis and with a working fit therebetween. To thus suspend the rotatable or inner casing 19 the same is provided with a fixed spindle 20 turnably mounted in a bearing sleeve 21 and thus held suspended by the hub 22 of an operating handle 23. This spindle 20 extends upward through a bore in the top of the inner casing 19 at the axis thereof and formed with its lower end is a large disk-like head 24 on which the top of said casing rests and is rigidly secured thereto by screws. The bearing sleeve 21, which is axially aligned with the casings 18 and 19, has near its lower end an annular flange 25 which rests on the top of the outer casing 18 and is rigidly secured thereto by screws. Said bearing sleeve 21 below its flange 25 loosely extends through a bore in the top of the outer casing 18 and terminates above the top of the inner casing 19 with a working fit therebetween and affords a positive stop to prevent lifting movement of the inner casing 19 in the outer casing 18. Formed with the upper end of the bearing sleeve 21 is an outstanding annular flange 26 which extends into a seat 27 in the under side of the hub 22 and has a snug fit therewith. The upper end of the spindle 20 extends above the bearing sleeve 21 and into a seat 28 in the hub 22 with a tight fit and is rigidly secured by a screw 29 to said hub.

Obviously, the upper face of the bearing sleeve 21 and its flange 26 form a bearing surface on which the hub 22 turnably rests. The open lower ends of the casings 18 and 19 are closely spaced above the counter 6 and its insert 17 with just sufficient clearance to permit the wicket 10 to swing to and from open positions.

By reference to Figs 2 and 3 it will be noted that the casings 18 and 19 are off-center on the cage side of the partition structure 7 with sufficient clearance to permit the handle 23 to be oscillated in an arc of 180°.

Formed in the side and top of the fixed casing 18 are two diametrically opposite segmental passages 30 and 31, the latter of which is on the lobby side of the partition structure 7 and the former of which is on the cage side thereof. A passage 32 is formed in the side and top of the rotatable casing 19 and of substantially the same shape and size as the passages 30 and 31 and arranged to be alternately brought into registration therewith by rotating the inner casing 19 by means of the handle 23. It is important to note that the passages 31 and 32 extend completely through the sides of the casings 18 and 19 so that an article placed on the counter insert 17 may be moved into or out of the rotatable casing 19 by sliding the same on said insert. In the top of the rotatable casing 19, diametrically opposite its passage 32, is a bullet-

removed by a person in the cage through the aligned passages 30 and 32 and at which time the person in the lobby can see through the glass insert 33 that the article is being removed.

The glass insert 15 gives a clear view through which persons on opposite sides of the partition structure 7 may see each other and the voice panels 16 permit conversation in ordinary tones. Each time the rotatable casing 19 is moved to bring its passage 32 into registration with one of the passages 30 or 31, said casing 19 is automatically locked by the latch 34 and can only be released by the person in the cage.

From a broad point of view the counter insert 17 forms a fixed bottom for the rotatable casing 19 and an article placed thereon is not disturbed or moved by the rotation of the inner casing 19.

What we claim is:

1. A deal tray adapted to be mounted in a closure and through which an article may be passed from one side of the closure to the other and comprising inner and outer casings, one of which is fixed and the other of which is rotatable, the fixed casing having a passage on each side of the closure and the rotatable casing having a passage arranged to be alternately brought into registration with the passages in the fixed casing by a movement of the rotatable casing, said rotatable casing also having an open bottom.

2. The structure defined in claim 1 which further includes a latch for positively holding the rotatable casing in a predetermined position in which its passage is in registration with one of the passages in the fixed casing.

3. The structure defined in claim 1 which further includes a latch for positively holding the rotatable casing in predetermined positions in which its passage is in registration with either one of the passages in the fixed casing.

4. The structure defined in claim 1 which further includes a transparent insert in the rotatable casing at the opposite side thereof from its passage and in which the fixed casing is provided with an opening on each side of the wicket with which the glass insert is successively brought into registration during the rotation of the rotatable casing.

5. The structure defined in claim 1 in which a direct passage through the deal tray is always closed by the rotatable casing and in which the closure and the deal tray are bullet-resisting.

6. The combination with a closure, of a deal tray mounted in the closure and through which an article may be passed from one side of the closure to the other and comprising inner and outer open bottom casings, one of which is fixed and the other of which is rotatable, the fixed casing having two passages, one on each side of the closure, the rotatable

casing having a passage arranged to be alternately brought into registration with the passages in the fixed casing by a movement of the rotary casing, and a fixed counter below the open bottoms of the two casings and closely associated therewith.

7. The combination with a closure, of a deal tray mounted in the closure and through which an article may be passed from one side of the closure to the other and comprising inner and outer casings, the former of which is rotatable and the latter of which is fixed, the fixed casing having two passages, one on each side of the closure, the rotatable casing having an open bottom, and a fixed counter below the open bottom of the rotatable casing and closely associated therewith.

8. The combination with a closure, of a deal tray mounted in the closure and through which an article may be passed from one side of the closure to the other and comprising concentric inner and outer casings, the former of which is rotatable about a vertical axis and the other of which is fixed, the fixed casing having two passages, one on each side of the closure, the rotatable casing having a passage arranged to be alternately brought into registration with the passages in the fixed casing by a movement of the rotatable casing, an operating handle secured to the rotatable casing at the axis thereof, and a latch on the operating handle operable to hold the rotatable casing with its passage in registration with the passage in the fixed casing on the same side of the closure as the operating handle.

9. The combination with a closure, of a deal tray mounted in the closure and through which an article may be passed from one side of the closure to the other and comprising concentric inner and outer casings, the former of which is rotatable about a vertical axis and the other of which is fixed, the fixed casing having two passages, one on each side of the closure, the rotatable casing having a passage arranged to be alternately brought into registration with the passages in the fixed casing by a movement of the rotatable casing, an operating handle secured to the rotatable casing at the axis thereof, and a latch on the operating handle operable to hold the rotatable casing with its passage in registration with either of the passages in the fixed casing.

10. The combination with a wicket mounted for opening and closing movements and having a passage therethrough, of a deal tray mounted in the passage for bodily movement with the wicket and for movement in respect thereto to position said tray for access thereto from either side of the wicket.

11. The structure defined in claim 10 in which a direct opening through the passage is constantly closed by the deal tray.

12. The structure defined in claim 10 in

which the wicket and deal tray are bullet-resisting.

13. The structure defined in claim 10 which further provides a transparent insert in the wicket, and in which the wicket, deal tray and insert are bullet-resisting.

14. A structure of the class described having a bullet-resisting wicket mounted for opening and closing movements, said wicket having a circuitous voice passage which cuts off direct vision through the wicket, and a bullet-resisting deal tray mounted in the wicket for movement therewith, said deal tray having a movable member that always closes a direct passage through the tray.

15. In testimony whereof we affix our signatures.

EDWARD C. HANSON.
SYLVAN R. POPP.
